UNITED STATES PATENT OFFICE

163,707

TOOTHBRUSH

George W. Pifer, Findlay, Ohio

Application March 17, 1950, Serial No. 8,599

Term of patent 14 years

(Cl. D9—2)

To all whom it may concern:

Be it known that I, George W. Pifer, a citizen of the United States, residing at Findlay, in the county of Hancock and State of Ohio, have invented a new, original, and ornamental Design for Toothbrush, of which the following is a specification, reference being had to the accompanying drawing, forming a part thereof, in which:

Fig. 1 is a top plan view of the toothbrush, showing my new design;

Fig. 2 is a side elevational view thereof;

Fig. 3 is a left end view of the toothbrush shown in Fig. 2; and

Fig. 4 is a right end view thereof.

I claim:

The ornamental design for a toothbrush, substantially as shown.

GEORGE W. PIFER.
